(57) **CLAIM**

We claim the ornamental design for a knife clip, as shown and described.

DESCRIPTION

FIG. 1 is a perspective view of a knife clip showing our new design;

FIG. 2 is a front elevation view thereof;

FIG. 3 is a back elevation view thereof;

FIG. 4 is a left-side elevation view thereof;

FIG. 5 is a top plan view thereof; and,

FIG. 6 is a bottom plan view thereof.

The broken lines in the drawing show portions of the knife clip and form no part of the claimed design.
